TANKER BULKHEAD AND COMPARTMENT CONSTRUCTION

Donald F. MacNaught, Hingham, Mass., assignor to Bethlehem Steel Company, a corporation of Pennsylvania

Application July 23, 1957, Serial No. 673,685

3 Claims. (Cl. 114—78)

This invention relates generally to the construction of 15 vessels for the transportation in bulk of liquid cargo, and, specifically, to a novel manner of supporting the vessels' transverse web frames.

It has long been the practice to build tankers with several liquid-tight transverse bulkheads and with one or more liquid-tight longitudinal bulkheads, thus subdividing the vessel into a number of liquid-tight storage compartments and, further, to provide open transverse web frames between the transverse bulkheads. Such construction is shown, for example, in U.S. Patent No. 1,029,546 to Isherwood. As tanker sizes increased, it became customary to increase the depth of the web of the transverse frames, and to stiffen these transverse web frames with struts as shown for example in U.S. Patent 2,218,688 to Stewart.

For several reasons, it has become economically attractive to construct tankers of enormous capacities, ranging from about 65,000 tons to over 100,000 tons. In vessels of such size, it is most important to reduce the cost of construction as much as is consistent with strength and seaworthiness.

In these huge tankers, more appropriately termed "super-tankers," there may be several transverse web frames between any two transverse bulkheads. I have invented a manner of construction wherein those transverse web frames adjacent the transverse bulkheads are supported by horizontal webs secured to the transverse bulkheads, thereby eliminating any need to incorporate struts into these transverse web frames and, at the same time, I am able to reduce the scantlings of these transverse web frames.

Accordingly, one of the objects of my invention is to support those transverse web frames adjacent a transverse bulkhead by means of horizontal webs secured to said transverse bulkhead.

Another object of my invention is to eliminate the use of struts in those transverse web frames adjacent a transverse bulkhead.

A further object of my invention is to reduce the scantlings of those transverse web frames adjacent a transverse bulkhead without sacrificing strength or seaworthiness.

Yet another object of my invention is to make more efficient use of steel in the construction of these huge tankers.

Other objects and advantages of my invention will become apparent during the course of the following description and by reference to the accompanying drawings, in which like numerals represent like parts in the several views.

Fig. 1 represents a partial plan view of a typical tanker constructed in accordance with my invention. This view is taken below the deck, from the shell of the vessel to its centerline. It will be understood that, as the vessel is generally symmetrical about its centerline, the half of the vessel not shown is similar to the half shown in this view. Fig. 1 shows a transverse bulkhead and

2

the two adjacent transverse web frames, one on either side of the transverse bulkhead, together with the horizontal webs secured to the transverse bulkhead and transverse web frames.

5 Fig. 2 represents a section in elevation, taken along the line 2—2 of Fig. 1, showing a transverse bulkhead and the horizontal webs secured thereto.

Fig. 3 represents a section in elevation, taken along the line 3—3 of Fig. 1, showing a transverse web frame and the horizontal webs secured thereto.

Fig. 4 represents a section in elevation, taken along the line 4—4 of Fig. 1, showing another view of the transverse bulkhead, and the horizontal webs secured thereto.

Fig. 5 represents an enlarged section in plan, taken along the line 5—5 of Fig. 3, showing a support bracket secured to the transverse web frame and to the adjacent structure, at a location between two of the horizontal webs.

A typical vessel built for the transportation in bulk of liquid cargo (e.g., oil) may comprise a number of liquid-tight transverse bulkheads 1, a number of liquid-tight longitudinal bulkheads 2, a deck 3, and a shell comprising bottom plating 4 and side plating 5. Thus, the hull of the vessel has been subdivided into a number of liquid-tight bulk cargo compartments 6. For purposes of clarity, only one set of transverse bulkheads 1 and only one longitudinal bulkhead 2 have been shown. The vessel illustrated in the foregoing drawings is framed

20 after the well-known "longitudinal" system, as shown, for example, in U.S. Patent No. 1,029,546 to Isherwood, and, accordingly, has longitudinals 7 and transverse web frames 8. Longitudinals 7 normally pass through transverse web frames 8 and extend to transverse bulkhead

25 1, except on those levels where horizontal webs 11 and flared ends 12 are secured to transverse bulkhead 1 (Fig. 1). In this last instance, longitudinals 7 stop short of transverse web frames 8, as shown in Fig. 1. Vertical stiffeners 9 are secured to transverse bulkhead 1. Support brackets 10 are secured to transverse web frames 8 and to those longitudinals 7 passing through transverse web frames 8.

30 It will be understood that there may be several transverse web frames 8 between any two transverse bulkheads 1. In a vessel built according to my invention, those transverse web frames 8 adjacent a transverse bulkhead 1 are supported from the transverse bulkhead 1 by a number of vertically spaced horizontal webs 11. Those transverse web frames not adjacent a transverse bulkhead 1 may be stiffened in the customary manner by struts as shown, for example, in U.S. Patent No. 2,218,

35 688 to Stewart. As these last-mentioned transverse web frames are not associated with my invention, they have been omitted, for purposes of brevity, from the drawings.

40 The drawings show a typical transverse bulkhead 1 with horizontal webs 11 secured to both sides of the bulkhead, each horizontal web 11 extending out to its respective transverse web frame 8. In order to obtain a balanced design, whereby the properties of horizontal webs

45 11 are effective for resistance to hydrostatic loading on transverse bulkhead 1 and are, in addition, suitable to provide support for the transverse web frames 8, I prefer to dispose and proportion the horizontal webs 11 substantially symmetrically about transverse bulkhead 1, as shown in Figs. 1 and 4.

50 Horizontal webs 11 are provided with splayed or flared portions 12. These splayed portions 12, which may be separate pieces secured to horizontal webs 11 or which may be formed integral with horizontal webs 11, extend to and are fitted and secured to transverse web frames 8.

55 Depending upon the particular bay of cargo compartments 6 under consideration (inboard or outboard), these

60 11 are effective for resistance to hydrostatic loading on transverse bulkhead 1 and are, in addition, suitable to provide support for the transverse web frames 8, I prefer to dispose and proportion the horizontal webs 11 substantially symmetrically about transverse bulkhead 1, as shown in Figs. 1 and 4.

65 Horizontal webs 11 are provided with splayed or flared portions 12. These splayed portions 12, which may be separate pieces secured to horizontal webs 11 or which may be formed integral with horizontal webs 11, extend to and are fitted and secured to transverse web frames 8.

70 Depending upon the particular bay of cargo compartments 6 under consideration (inboard or outboard), these

splayed portions 12 may also be secured, as will be evident upon inspection of the drawings, to side plating 5 or to longitudinal bulkhead 2.

Stiffeners 13 are secured to vertical stiffeners 9 and to horizontal webs 11 and flared portions 12. Face plates 14 are also secured to horizontal webs 11 and to flared portions 12.

Brackets 15 are secured to transverse web frames 8, at regions thereon opposite the regions of attachment of splayed portions 12, to longitudinals 7, and to side plating 5 or longitudinal bulkhead 2 as will be evident from Fig. 1.

From the foregoing, it will be seen that each of the transverse web frames 8 adjacent a transverse bulkhead 1 is effectively supported by said transverse bulkhead 1, through the horizontal webs 11 and their splayed or flared portions 12, at a plurality of vertically spaced regions, whereby conventional struts are dispensed with and the scantlings of said transverse web frames 8 are reduced.

As an example of the results attainable through the employment of my invention, in these huge tankers some 25 tons of steel per tank can be saved over conventional construction methods. In a supertanker of some 100,000 tons capacity, there may be 15 tanks. Thus, in the construction of such a vessel, a saving of approximately 375 tons of steel can be realized.

It will be appreciated that, although five sets of tiers of horizontal webs 11 are shown in the accompanying drawings, the actual number of horizontal webs 11 in any particular vessel will depend upon the dimensions of the vessel and its component parts insofar as they relate to cargo compartments 6.

Although I have shown and described my invention in some detail, I do not wish to be limited to the exact arrangement shown and described, but may use such substitutions, modifications or equivalents thereof as are embraced within the scope of my invention or as pointed out in the claims.

I claim:

1. In a vessel provided with a deck, bottom plating, side plating, a first bulkhead arranged substantially parallel to the side plating, a second bulkhead intersecting the side plating and first bulkhead, and first and second

web frames arranged substantially parallel to and on opposite sides of the second bulkhead and intersecting the side plating and first bulkhead and extending from the deck to the bottom plating, supporting construction for the first and second web frames and for said second bulkhead comprising a plurality of vertically spaced horizontally disposed first web members secured to the second bulkhead, first portions on said first web members secured to said first web frame in the vicinity of the side plating, second portions on said first web members secured to said first web frame in the vicinity of the first bulkhead, a plurality of vertically spaced horizontally disposed second web members secured to the second bulkhead, third portions on said second web members secured to said second web frame in the vicinity of the side plating, and fourth portions on said second web members secured to said second web frame in the vicinity of the first bulkhead said first and second, and third and fourth portions being in effective supporting relationship with said first and second web frames respectively at a plurality of points intermediate the deck and bottom plating, whereby the vertical spans and scantlings of said first and second web frames are reduced.

2. Supporting construction as in claim 1, said first web members being disposed substantially symmetrically with respect to said second web members about said second bulkhead.

3. Supporting construction as in claim 1, further including first and third bracket members secured to the side plating and respectively to the first and second web frames at regions substantially opposite the regions of attachment of said first and third portions to said first and second web frames respectively, and second and fourth bracket members secured to the first bulkhead and respectively to the first and second web frames at regions substantially opposite the regions of attachment of said second and fourth portions to said first and second web frames respectively.
